His Attorney

UNITED STATES PATENT OFFICE.

JOHN J. FRANK, OF PITTSFIELD, MASSACHUSETTS, ASSIGNOR TO GENERAL ELECTRIC COMPANY, A CORPORATION OF NEW YORK.

METHOD OF PRODUCING PUNCHINGS.

1,334,149.

Specification of Letters Patent. Patented Mar. 16, 1920.

Application filed October 26, 1918. Serial No. 259,881.

To all whom it may concern:

Be it known that I, JOHN J. FRANK, a citizen of the United States, residing at Pittsfield, county of Berkshire, State of Massachusetts, have invented certain new and useful Improvements in Methods of Producing Punchings, of which the following is a specification.

My invention relates to a method of producing L-shaped punchings, such as the laminations used in the construction of cores for electrical apparatus.

In the manufacture of L-shaped punchings of a given size, it has generally been the practice to strike these punchings from a sheet of metal stock that is but slightly wider than the hypotenuse or distance across the tips of the legs of the L-punching to be produced; the legs having such proportions that one L will nest in the next, the bend or knee of the L's lying along substantially a straight line to one side of the center line of the sheet of stock. Even with this nesting of the L-punchings a considerable percentage of the stock went into the refuse because all along the edge of the stock there were substantially triangular pieces to be sheared off to give the ends of the legs of the L-punching their desired shape, which pieces were generally connected by a marginal strip.

It is the object, then of my invention, to reduce this waste by at least half and in some instance where the triangular pieces on the two sides of the stock are of different size a greater saving may be effected.

In order to accomplish this object I propose to use a sheet of stock a little less than twice the normal width, and to strike a second lot of L's from the other side of the strip of sheet metal stock in such a manner that the homologous leg of the L's from each side of the strip have their squared ends abutting, thereby eliminating entirely the waste material along one edge.

In order that my invention and the method of practising the same may be more fully comprehended, reference should be had to the following detailed description taken in connection with the accompanying drawing in which Figure 1 shows a plan view of a piece of metal stock having L's punched from it in accordance with the method which I have invented. Fig. 2 is a similar view illustrating a modified manner of practis-

ing this invention. Fig. 3 is a plan view showing a piece of stock when punched in accordance with this modification, and Figs. 4 and 5 illustrate respective conventional forms of punch press and punch suitable for use in the practice of this invention.

Referring now to Fig. 1 of the drawings, A denotes a piece of metal stock whose width a is almost twice the distance b which would be the width of stock required were it desired to stamp single successive L's as 1, 2, 3 etc. out of a strip of stock.

If the strip were of the width b , it is seen that along the upper edge of the strip the triangles t would be waste, while on the lower edge the triangles u would be waste. Of the two triangles, it is seen that the triangle t is the larger since the triangle u is somewhat reduced because it is desired to have the longer leg of the L-punching formed with a diagonally cut corner as shown. As a consequence the triangles t comprise the largest percentage of the waste. In practice it is generally preferable to have the triangles u connected by a narrow marginal strip, such as shown at m .

On account of the difference in size between the triangle t and u the largest economy can consequently be effected by eliminating the waste of the triangles t . To this end an L having a leg, whose end is square, is struck from the upper portion of a strip, whose width is a , so that corresponding squared ends of the legs of the L abut, as illustrated by the L's shown at 1 and 1'.

Where it is desirable to produce the L's 1 and 1' at the same stroke of the punches, a Z-shaped punching would first result which would need to be subsequently sheared into the two L's. This shearing could be done by a separate operation or by the provision of a compound die, cutting along the dividing line by means of a narrow blade either before or after the Z-punching was struck.

The best means, however, for practising this method at present known to me, accomplishes the production of the independent L's with one operation without the use of compound dies. This means comprises a punch, shown at P in Fig. 5, arranged for shearing the stock A along the irregular contour designated e, f, g, h, i in Fig. 3.

When a punch having the shape indicated at P is reciprocated by the ram R of a punch press, as indicated in Fig. 4, each successive

stroke of the ram would shear off the L's separately, one abutting L coming off in advance of the other, as will be readily understood by reference to Fig. 2.

- 5 In this figure, suppose the stock A has been fed into the punch press until it is shorn along the line e, f, g, h, i; then upon the upstroke of the ram the stock would be advanced a distance to give the desired width 10 of the punching to be shorn off, so that upon the downward stroke of the ram the two independent L's 4 and 4' would be produced. After the next advance the punch would shear off the L's marked 5 and 5', then 15 the L's marked 6 and 6' etc. in succession until the end of the stock is reached.

It is thus seen that the L-punching 5', whose squared end abuts the homologous end of L-punching 6, was stamped out one 20 stroke in advance of the stroke which shears off the punching 6, but this is by no means the only contour that may be given to a punch which will shear off L's from both sides of the stock in accordance with my invention, so that the L's on one side come off 25 in advance of the other, since those on one side may be taken off any number of steps in advance of those shorn from the other side.

- 30 Having now described an embodiment of my invention and the best method and means at present known to me for carrying the same into effect, I would have it understood that is merely for the purpose of illustration. Consequently I do not mean to be limited thereby to the exact details disclosed, nor in the choice of recognized equivalents in the practice of my invention except 35 as defined in my claims hereunto annexed.

What I claim as new and desire to secure 40 by Letters Patent of the United States, is:

1. The method of producing L-shaped punching which consists in taking a piece of metallic stock of appreciably less than twice the width normally employed when 45 punching single rows of L's, and in striking independent L's from both sides of said stock so that one pair of homologous legs abut..

2. The method of producing L-shaped punching which consists in taking a piece of 50 metallic stock of appreciably less than twice the width normally employed when punching single rows of L's, and in striking independent L's from both sides of said stock so that the L's having abutting legs form a 55 Z-punching.

3. The method of producing L-shaped punching which consists in taking a piece of metallic stock of appreciably less than twice the width normally employed when punching single rows of L's, and in striking L's from both sides of the stock so that one pair of homologous legs abut permitting an independent L from one side to come off in advance of that struck from the other side. 60

4. The method of producing interfitting uncomplementary laminated elements from stock sheet material with minimum waste, which consists in successively striking laminated elements from one side of the stock, 70 and in simultaneously striking like elements in abutting relations to the former from the other side of the stock from successive positions where independent cutting operations may be performed. 75

In witness whereof I have hereunto set my hand this 22nd day of October, 1918.

JOHN J. FRANK.
